G. E. BISSELL

BY *Muri Leo.*
ATTORNEY

UNITED STATES PATENT OFFICE

GUY F. BISSELL, OF MORTON GROVE, ILLINOIS, ASSIGNOR OF ONE-HALF TO ROY C.
BISSELL, OF MORTON GROVE, ILLINOIS

PRESSURE FLUID GENERATOR

Application filed November 21, 1927. Serial No. 234,797.

My invention relates to improvements in pressure fluid generators, and it consists in the combinations, constructions, and arrangements herein described and claimed.

An object of my invention is to provide a generator in the form of a combustion boiler which maintains the heat more readily than the ordinary type of combustion boilers.

A further object of my invention is to provide a device of the type described, by means of which a more thorough breaking down of the heavy fuels, owing to the longer exposure to high temperature and pressure, will take place.

A further object of my invention is to provide a device of the type described, by means of which inferior fuels, which are prohibited by the ordinary types of internal combustion engines, may be used efficiently.

A further object of my invention is to provide a device of the type described in which the use of cooling devices such as radiators and the like is eliminated and energy is conserved and utilized instead of being dissipated and lost.

A further object of my invention is to provide a device of the type described which is simple in construction and compact in form, thus making it possible to be used on aeroplanes and lighter than air ships, and in this manner non-explosive fuels may be used.

Other objects and advantages will appear in the following specification, and the novel features of the invention will be particularly pointed out in the appended claims.

My invention is illustrated in the accompanying drawings, forming part of this application, in which

Figure 1 is a longitudinal sectional view of my device, and

Figure 2 is a section along the line 2-2 of Figure 1.

In carrying out my invention, I provide a casing composed of a cylindrical body portion 1 and cup-shaped end members 2 and 3 arranged to be secured to the ends of the body portion. The end members 2 and 3 are provided with central openings 4 and 5, respectively. A diffusion or mixing tube 6 having

50 a cap or cover 7 rigidly secured to one end

thereof is passed through the opening 4 until the cover 7 is disposed in engagement with the end member 2. In this manner, the diffusion tube 6 is centrally disposed in the casing. The cover 7 may be rigidly secured in 55 place by any suitable means not shown. A head portion 8 is rigidly secured to the inner end of the diffusion tube 6 and is provided with an irregular outer surface 9. The head portion 8 is constructed of very durable heat-resistant material, such as fire clay.

A combustion block 10, having an irregular surface 11 disposed in close proximity to the irregular surface 9 of the head portion 8 to form an irregular passageway 12, is rigidly secured to a cover member 13. The combustion block 10 is constructed of a very durable heat-resistant material such as porcelain, fire clay composition, or the like, and is arranged to extend through the opening 5 so that the 70 cover 13 is positioned in engagement with the end member 3. The combustion block 10 and the cover 13 may be rigidly secured in place by any suitable means not shown.

An air tube 14, which communicates with 75 an air supply pipe 15 having a one way valve 16 disposed therein, extends through the cap 7, the diffusion tube 6, and is centrally disposed therein. An annular guide member 17 is disposed upon the inner end of the air tube 80 14 adjacent the head portion 8. The annular guide member is positioned in alignment with an opening 18 in the head portion 8. An opening 19 is centrally disposed in the combustion block 10 and the cover 13 for receiving 85 a spark plug 20.

A steam generating coil 21 is disposed within the casing and positioned adjacent the inner wall of the cylindrical portion 1 and the end members 2 and 3. The coil 21 is in 90 communication with a water supply pipe 22 which extends longitudinally through the casing and through an opening 23 in the end wall 2 where it communicates with a water 95 supply pipe 24 by means of a valve 25. The coil 21 terminates at 26, where it allows the contents thereof to escape into the casing. An outlet opening 27 is provided for the casing 100 for allowing the generated power fluid

to pass from the casing to any means, such as a motor, heating plant, or the like.

A fuel coil 28 is disposed concentric with the diffusion tube 6 and is in communication with a fuel supply tube 29 at one end thereof and in communication with the diffusion tube at the other end thereof indicated at 30. The fuel supply tube extends through the cap 7 and is in communication with a fuel supply pipe 31 by means of a valve 32. A water feeding pipe 33 is disposed in communication with the fuel supply tube 29 by means of a valve 34 so that a small quantity of water may be mixed with the fuel. The mixture of the water and the fuel serves the following purposes: Under the influence of heat such as hereinafter explained, the fuel is volatilized and the water becomes more or less highly heated steam. Under this condition the particles of H_2O and fuel vapor attain enormous velocities in different directions. These particles come into collision with one another with great violence and these collisions aid in cracking or breaking up the fuel and also cause the vaporized water and steam to diffuse one with the other. The water or steam in the diffusion tube tends to slightly retard combustion so that when the fuel is ignited the force of the explosion is distributed over a longer period of time without appreciably diminishing the pressure which the combustion of the fuel provides for power purposes.

It will be readily understood by looking at Figure 2 that the average rate of flow of the fuel and water in the diffusion part is much less than it is while the steam and fuel are passing through parts 28. The fuel and water have therefore a relatively longer time to remain in the diffusion tube and mix thoroughly therefore making a more efficient fuel mixture.

From the foregoing description of the various parts of the device, the operation thereof may be readily understood. With this type of combustion generator, various grades of fuel may be used. With the inferior grades of fuel, a mixture of water is necessary. However, with the superior grades of fuel, the mixture of water is not needed. With the introduction of volatile fuel through the fuel tube 29 and out into the fuel diffusion tube 6 through the coil 28, there is obtained a combustible mixture by the time it reaches the innermost end of the diffusion tube. As the combustible mixture passes around the annular guide portion 17 and through the opening 18, it mixes with the air and is ignited by the spark plug 20.

With the increase of temperature in the casing, heavy fuels and water are continuously introduced to the fuel tube 29 and combustion is maintained spontaneously between the head portion 8 and the combustion block 10, where the fuel continues to come in con-

tact with the air forced in through the air tube 14. The gaseous by-products, which are exhausted through the irregular passageway 12, heat the coils 21 and 28. Therefore, by introducing water through the water tube 22 and into the coil 21, steam is produced, due to the heat in the casing. The steam is allowed to pass through the coil 21 and into the casing, where it acts as an auxiliary means for maintaining the heat within the casing for heating the water entering the coil 21. Furthermore, by this same means the mixture of fuel is pre-heated within the coil 28 before it is allowed to pass into the fuel diffusion tube 6. The steam and the by-products pass through the outlet 27 at a rate of speed determined by the pressure maintained in pipes 15, 24, 31, and 33, and the relatively open or closed positions of valves 16, 25, 32, and 34. The valve 25 varies the speed at which the water is allowed to pass through the water tube 22 and into the coil 21.

The gases of combustion mingle with the steam in the casing and aid in heating the diffusion tube 6, the coils 28 and their contents, and also the coils 21 and their contents. The steam, together with the combustion gases, passes from the casing through the outlet 27.

I claim:

1. A device of the type described comprising a casing having a cylindrical body portion, end portions, a diffusion tube centrally disposed in said casing, means for supplying heated fuel to said diffusion tube, an air tube disposed in said diffusion tube and so arranged whereby heated air may be mixed with said fuel as said fuel passes from said diffusion tube, a steam generating coil disposed in said casing adjacent the inner wall of said cylindrical body portion and communicating with a water supply, means for igniting the fuel as the fuel passes from said diffusion tube, means for directing and changing the direction of flow of the gases of combustion from flowing toward the ignition means to flow toward said steam generating coil, the heat from the gases of combustion heating said steam generating coil, whereby water entering said coil will be transferred to steam, a steam outlet for said coil for conducting steam therefrom to said casing, and an outlet for passing gases from said casing.

2. A device of the type described comprising a casing having a cylindrical body portion, a diffusion tube centrally disposed in said casing, means for supplying heated fuel to said diffusion tube, an air tube disposed in said diffusion tube and so arranged whereby air may be mixed with said fuel as said fuel passes from said diffusion tube, a steam generating coil disposed in said casing adjacent the inner wall of said cylindrical body portion and communicating with a water

supply, means for igniting the fuel and reversing its direction of flow as the fuel passes from said diffusion tube, means for directing the gases of combustion from the ignition of 5 said fuel toward said steam generating coil, the heat from the gases of combustion heating said steam generating coil, whereby water entering said coil will be transferred to steam, a steam outlet for said coil for conducting steam therefrom to said casing, and 10 an outlet for said casing for allowing the gases to pass from said casing.

3. A device of the type described comprising a casing having a cylindrical body portion and end members having openings therein, a diffusion tube having a cap carried by one end thereof disposed in said casing through the opening in one of said end members, said cap engaging with said end member for closing the opening therein, a head portion disposed upon said diffusion tube and having an opening therein, an air tube communicating with an air supply extending through said cap and said diffusion tube, 20 means carried by the end of said air tube adjacent said head portion and providing an annular passageway from said diffusion tube, a combustion block arranged to be disposed in the other end member at a position in close proximity to said head portion, whereby an annular passageway may be provided therebetween, igniting means disposed in said combustion block, a fuel supply tube disposed in communication with a fuel supply and extending through said cap and encircling said diffusion tube, means for transmitting water to said fuel supply tube, a fuel reducing coil disposed concentric with said diffusion tube and having one end in communication 30 with said fuel supply tube, the other end communicating with said diffusion tube adjacent said cap, a steam generating coil disposed in said casing adjacent the inner wall of said cylindrical body portion and having one end 40 in communication with a water supply, the other end being provided with a steam outlet in communication with the interior of said casing, said igniting means arranged to ignite the fuel as it passes from said diffusion tube and mixes with the air of said air tube, the gases of combustion from said ignited fuel being forced through said annular passageway between said head portion and said combustion block toward said steam generating coil for heating said coil and the water 50 therein for transferring the water into steam, the steam passing from said steam outlet into said casing, and an outlet for passing the gases from said casing, said diffusion tube, 60 said annular passageway, and said combustion block being positioned relative to each other in such a manner as to substantially reverse the direction of travel of the fuel at the time of ignition.

65 4. A device of the type described comprising

ing a cylindrical casing, end members secured to the casing and being provided with aligned openings, a diffusion or mixing tube disposed in one of said openings and having a head arranged to engage one of said end members, a heat resisting block disposed in the opening of the companion end member, a refractory head portion carried by the diffusion tube, said head portion being provided with a central opening and being spaced from the block to provide a passage for directing products of combustion toward the interior of the casing and the exterior of the diffusion tube, a fuel coil surrounding said diffusion tube and having an inlet into said tube at the opposite end from said head, an air tube extending through said diffusion tube for delivering air through the central opening in said head, and an outlet in said device for allowing gases to pass from said casing, said heat resisting block being so positioned with respect to said refractory head portion as to change the direction of flow of the fuel more than 90° at the time of ignition.

5. A device of the type described comprising a cylindrical casing, end members secured to the casing and being provided with an exhaust opening and aligned openings, a diffusion or mixing tube disposed in one of said openings and having a head arranged to engage one of said end members, a heat resisting block disposed in the opening of the companion end member, a refractory head portion carried by the diffusion tube, said head portion being provided with a central opening and being spaced from the block to provide a passage for directing products of combustion toward the interior of the casing and the exterior of the diffusion tube, a fuel coil surrounding said diffusion tube and having an inlet into said tube at the opposite end from said head, an air tube extending through said diffusion tube for delivering air through the central opening in said head, means carried by said block for igniting the combustible mixture, and an outlet for passing the steam from said casing, said refractory head portion and said heat resisting block being formed and arranged substantially as shown.

6. A device of the type described comprising a cylindrical casing, end members secured to the casing and being provided with aligned openings, a diffusion or mixing tube disposed in one of said openings and having a head arranged to engage one of said end members, a heat resisting block disposed in the opening of the companion end member, a refractory head portion carried by the diffusion tube, said head portion being provided with a central opening and being spaced from the block to provide a passage for directing products of combustion toward the interior of the casing and the exterior of the diffusion tube, a fuel coil surrounding said diffusion tube

- and having an inlet into said tube at the opposite end from said head, an air tube extending through said diffusion tube for delivering air through the central opening in
5 said head, means carried by said block for igniting the combustible mixture, a steam coil spaced from said fuel coil and having an outlet into the space between the steam coil and the fuel coil, and an exit pipe for carrying
10 away steam and the products of combustion, said heat resisting block, said refractory head portion, and said means carried by said block for igniting the combustible material being positioned with respect to each other so as
15 to substantially reverse the direction of flow of the fuel made at the instant of ignition.
7. A device of the type described combining a casing having a cylindrical body portion and being provided with exhaust
20 means, a diffusion tube centrally disposed in said casing, a tubular means for supplying heated fuel to said diffusion tube, an air tube disposed in said diffusion tube and arranged in a manner whereby heated air may be
25 mixed with fuel as it passes from said diffusion tube, a steam generator coil disposed in said casing adjacent the inner wall of said cylindrical body and communicating with a supply of water under pressure at one end
30 and opening into said casing at the other end, means for igniting said fuel, and means for substantially reversing its direction of flow at the instant of ignition.

Signed at Chicago, in the county of Cook, and State of Illinois, this 18th day of November, A. D. 1927.
